(57) CLAIM

The ornamental design for an eyeglasses case, as shown and described.

DESCRIPTION

FIG. 1 is a top perspective view of an eyeglasses case in a closed configuration.

FIG. 2 is a front view of the eyeglasses case of FIG. 1 in the closed configuration.

FIG. 3 is a back view of the eyeglasses case of FIG. 1 in the closed configuration.

FIG. 4 is a first end view of the eyeglasses case of FIG. 1 in the closed configuration.

FIG. 5 is a second end view of the eyeglasses case of FIG. 1 in the closed configuration.

FIG. 6 is a top view of the eyeglasses case of FIG. 1 in the closed configuration.

FIG. 7 is a bottom view of the eyeglasses case of FIG. 1.

FIG. 8 is a perspective view of the eyeglasses case of FIG. 1 in an open configuration.

FIG. 9 is a front view of the eyeglasses case of FIG. 1 in the open configuration.

FIG. 10 is a back view of the eyeglasses case of FIG. 1 in the open configuration.

FIG. 11 is a first end view of the eyeglasses case of FIG. 1 in the open configuration.

FIG. 12 is a second end view of the eyeglasses case of FIG. 1 in the open configuration.

FIG. 13 is a top view of the eyeglasses case of FIG. 1 in the open configuration; and,

FIG. 14 is another perspective view of the eyeglasses case of FIG. 1 in the open configuration, but with unclaimed eyeglasses within the eyeglasses case.

Portions of the drawings shown in a broken line depict environmental structure associated with the eyeglasses case. The broken lines and environmental structure they depict form no part of the claimed design.
